CARPET CLEANING MACHINE

John K. Tingle, Connersville, Ind.

Application April 29, 1935, Serial No. 18,720

2 Claims. (Cl. 68—45)

This invention relates to carpet cleaning machines, and in particular to such machines wherein the carpet and the cleaning members move relatively to one another during the cleaning operation.

One object of my invention is to provide a carpet cleaning machine wherein the carpet and the machine move relatively to one another, the carpet being subjected to the cleaning action of cleaning members intermittently pressed against it, while supplied with a cleaning solution.

Another object is to provide a carpet cleaning machine through which the carpet is moved while being subjected to the cleaning action of a resilient cleaning member alternately pressed against and withdrawn from the surface of the carpet while a cleaning solution is supplied thereto.

Another object is to provide a carpet cleaning machine wherein the carpet moves through the machine while being subjected at one point to the pressing action of a cleaning member while a cleaning solution is supplied thereto, this cleaning solution being partially squeezed out of the carpet at a subsequent point and the carpet therebeyond subjected to the action of another cleaning member pressing against the carpet, while rinsing water is supplied thereto.

Another object is to provide a carpet cleaning machine, as previously described, wherein the cleaning members are operated alternately from the same driving mechanism.

Another object is to provide a carpet cleaning machine, as above described, wherein the machine is portable and arranged to be moved over the carpet while cleaning the latter.

Another object is to provide a carpet cleaning machine wherein the cleaning members sliding across the surface of the carpet are eliminated and cleaning members having a pressing action supplied so that the machine is adapted to clean delicate carpets and the so-called "hooked rugs" without damage to such rugs, as has occurred in previous types of machines.

45 In the drawings:

Figure 1 is a plan view of the carpet cleaning machine of my invention with an upper frame cross member removed in order to disclose more clearly the parts beneath it.

50 Figure 2 is a longitudinal section through the machine shown in Figure 1, taken along the line 2—2 thereof, certain portions involving the driving mechanism in the upper part of the figure being removed in order to simplify the showing.

Figure 3 is a section along the line 4—4 of Figure 2.

Figure 4 is a section along the line 5—5 of Figure 2.

Figure 5 is a view of a portion of a modified form of machine, showing the cleaning members arranged side by side on the same shaft.

Figure 6 is a side elevation of a modified form of machine arranged for portable use.

Figure 7 is an end elevation of the portable machine shown in Figure 6.

Figure 8 is a plan view of a modified form of carpet cleaning machine.

Figure 9 is a section along the line 10—10 of Figure 8.

Figure 10 is a section along the line 11—11 of Figure 8.

Figure 11 is a bottom plan view of a modified form of cleaning member according to my invention.

Figure 12 is an elevational sectional view taken on the line 12—12 of Figure 11.

Figure 13 is a bottom plan view of the second modified form of cleaning member.

Figure 14 is an elevational sectional view taken on the line 14—14 of Figure 13.

Referring to the drawings in detail, Figures 1 and 2 show the machine of my invention mounted upon a base 1 supported by legs 2, and having the side members 3 and 4 attached thereto. The base 1 serves to support the shafts 5 and 6, carrying the rollers 7 and 8 mounted at opposite ends of the machine. Over these rollers passes the endless conveyor belt 9, the whole being so arranged as to bring the top surface of the conveyor belt into line with the top surface of the base.

For this purpose the base 1 is cut away in its central portion so that it possesses end portions 10 and 11, together with an intermediate portion 12, these being separated by apertures. The conveyor belt 9 moves in the first aperture with its upper surface flush with the adjacent surfaces of the base portions 10 and 11, whereas an additional roller 13, mounted on the shaft 14, extends into the aperture between the base portions 10 and 11 so that its upper surface is adapted to engage the lower surface of the carpet passing thereover. The shaft 14, supporting the roller 13, is also mounted upon the frame 1 and driven in a manner subsequently to be described. The roller 13 is partly immersed in a tank 15 arranged to contain a sizing solution, which is transferred to the carpet by the roller 13.

13, hereafter called the sizing roller. The carpet itself is indicated by the numeral 16.

5 Rotatably mounted in spaced relationship between the frame side members 3 and 4 are the rollers 17, 18, 19 and 20, supported respectively upon the shafts 21, 22, 23 and 24. Each of these rollers 17 to 20 is provided with a resilient covering 25, sponge rubber having been found suitable for this purpose. At the opposite ends of 10 these rollers the coverings 25, by reason of their resilience, bulge downward at the points 26 and 27 (Figure 4), thereby engaging the belt 9 on either side of the carpet so as to assist in preventing the escape of the solutions laterally from the carpet. The frame is provided with side plates 28 between which the rollers are disposed with their ends in close engagement therewith for preventing the escape of the liquid (Figure 1).

20 Arranged between the rollers 18 and 19 and 19 and 20, respectively, are two cleaning members 29 and 30, having resilient surface coatings 31. The coatings 31 are provided with corrugated lower surfaces 33, serving to engage the surface 25 of the carpet when the cleaning members 29 and 30 are pressed downwardly against it. An upwardly extending flange 34 on each cleaning member 29 and 30 serves to engage corresponding grooves in the guide members 35 and 36 supported upon the frame cross member 37, extending between the frame side members 3 and 4 of the machine (Figure 1).

The rollers 17 and 20 are mounted immediately over the rollers 7 and 8, respectively, in such a manner that the carpet is squeezed between the surface coverings 25 of the upper rollers and the upper surface of the conveyor belt 9. The shaft 24, supporting the roller 20, is mounted in a bearing block 38 adapted to move up and down in the guideways 39 against the urge of the springs 40 on one side (Figure 4), and the pressure of the adjusting screws 41 on the other. By tightening or loosening the adjusting screws 41 any desired amount the pressing effect may be given to the roller 20 so that a suitable squeezing action may be performed upon the carpet.

The cleaning members 29 and 30 are pivotally connected, as at 42 and 43 respectively, to connecting rods 44 and 45, the opposite ends of 50 which are bored so as to encircle the cams 46 and 47, mounted upon the shafts 48 and 49, respectively. The shafts 48 and 49 are rotatably supported between the frame side members 3 and 4 by being mounted upon the bracket member 53 depending from the frame cross member 54, extending between the frame side members 3 and 4, respectively. The shafts 48 and 49 carry sprockets 50 and 51, interconnected by the sprocket chain 52. Consequently, it will be obvious that 60 when one of the cam shafts 48 or 49 is rotated the other one will likewise be rotated and the cams 46 and 47 thereon will cause the cleaning members 29 and 30 to move up and down in the guideways of their guide members 35 and 36.

65 The motor 55 carries a pulley 56, driving the belt 59 and the pulley 57 on the counter-shaft 58. The latter is supported in the frame bearing brackets 60 and carries at one end a bevel gear 61 and at the other end a worm 62. The bevel gear 61 meshes with a bevel gear 63, mounted upon the vertical shaft 63a. The latter has on its upper end the bevel gear 63b, meshing with the bevel gear 63a upon the cam shaft 48. The worm 62 meshes with a worm gear 64, mounted 75 upon the roller shaft 6. The latter at each end

carries a sprocket 65, serving to drive similar sprockets 66 upon the sizing roller shaft 14, through the sprocket chains 67 interconnecting these sprockets. The cam shaft 48, as previously explained, drives the cam shaft 49 through the flexible driving member 52 interconnecting them (Figure 1).

70 The spaces between the rollers 17, 18 and 19 are occupied by a cleaning solution, such as a mixture of soap and water, supplied thereto through the pipes 68 (Figure 2). The escape of this cleaning solution is prevented, as previously stated, partly by the side plates 28 and partly by the bulged portions 26 on the end of each roller. The space between the rollers 19 and 20, however, 15 is served by the pipes 69 having the spray portions 70 adapted to supply fresh water to the carpet for removing the cleaning solution therefrom.

Operation

20 In the operation of the carpet cleaning machine of my invention the carpet 16 is caused to move between the rollers 17 and the belt 9 by the driving mechanism of the machine. When the carpet arrives at the space between the rollers 17 and 18 it is soaked with the cleaning solution of soap and water fed into the space by the pipe 68. The carpet, thus saturated with the cleaning solution, passes underneath the covering 25 on the roller 18, and immediately encounters the pressing action of the cleaning member 29 as it moves up and down against the carpet beneath it.

25 The corrugations 33 upon the resilient portion 31 engage the carpet and result in an alternate pressing and suction action, which thoroughly 35 forces the cleaning solution into and out of the carpet. This alternate pressing and suction action causes the carpet to be thoroughly cleaned by the liquid forced between the threads thereof, yet does so without any pulling action upon the 40 threads, as is the case in previous machines where a cleaning member, such as a brush, is caused to move back and forth across the carpet. Consequently, delicate rugs, such as hooked rugs, are not injured by the operation of the cleaning member 29, whereas the brushes of previous machines have frequently caused damage to such 45 rugs.

50 After being subjected to this alternate pressing and suction, in the presence of the cleaning solution, the carpet is conveyed onward by the action of the moving belt 9, and passes beneath the covering 25 of the roller 19 into the space underneath the second cleaning member 30. Rinsing water is sprayed onto the carpet from the 55 pipes 69, and this, combined with the alternate suction and pressing action of the cleaning member 30, causes the cleaning solution to be extracted from the carpet or washed away with the rinsing water which escapes between the ends 60 of the side plates 28 and guideways 39 adjacent thereto (Figs. 1, 2).

65 After this rinsing operation the carpet passes over the roller 8, between the belt 9 and the surface covering 25 of the roller 20, which squeezes out the remaining water. Beyond this point the carpet passes across the intermediate portion 11 of the base 1 (Figure 2) and over the upper surface of the sizing roller 13. From this roller the carpet 16 receives a supply of sizing liquid as 70 contained in the tank 15. After this the carpet passes over the end section 11 of the base 1 and the cleaning operations are completed.

75 In the modified form of cleaning machine, shown in Figure 5, the general construction is 75

substantially as that of the machine previously described and shown in Figures 1 to 4, inclusive. Instead of a single pressing member, operated by each cam shaft, the machine shown in Figure 5 is provided with a series of such cleaning members. Since each of the cam shafts carries a similar mechanism a description of one will suffice for all.

The cam shaft 80 (Figure 5) is provided with eccentricities 81 and 82, serving the same purpose as the cams 46 and 47, previously described. Guiding members 83, 84, 85 and 86 serve to slidably support the flanged portions 87 and 88 of the cleaning members 89 and 90, respectively. The cleaning member 89 is provided with arms 91, pivotally engaged by the connecting rods 92 encircling the eccentric 81 in a manner similar to that previously described. Similarly, the cleaning member 90 is provided with arms 93 pivotally engaging the connecting rods 94, which similarly encircle the eccentric 82.

The cam shaft 80 is driven by a bevel gear 95 meshing with a bevel gear 96 on the jack shaft 97, the lower end of which carries a bevel gear 98 meshing with a bevel gear 99 mounted upon the countershaft 58. Consequently, it will be apparent that when the cam shaft 80 is rotated, through the action of the bevel gearing from the counter-shaft 58, the cleaning members 89 and 90 will be caused to move up and down. By adjusting the positions of the eccentricities 81 and 82 the cleaning member 89 may be caused to move upward when the cleaning member 90 is moving downward so that an alternate motion results.

The modified form of machine shown in Figures 6 and 7 is adapted for portable use, but embodies the same principles and essential devices as those previously described. The machine of Figures 6 and 7 consists essentially of a base 100 having arms 101, serving to support castors 102 by which the machine is rolled over the floor or bed plate 103, as the case may be, the portion of the carpet 16 disposed between the opposite castors 102 being subjected to the cleaning action of the machine.

The base 100 is provided with a handle 104, attached thereto (Figure 6) and having on its upper end the cross bar 105 which may be grasped by the operator. Mounted upon the base 100 and extending upwardly therefrom are the side members 106 and 107, these serving to support the tank 108 extending between their upper edges. Pipes 109 and 110, terminating in the transverse conduits 111 and 112, respectively, serve to convey the liquid from the tank 108 and distribute it over the surface of the carpet.

The carpet cleaning machine of Figures 6 and 7 is similarly provided with cleaning members 113 and 114, having the resilient pads 115 and 116 mounted on their lower surfaces. The latter are provided with corrugations 117, in a manner similar to that already described. Each of the cleaning members 113 and 114 is provided with a flanged portion 118 and 119, respectively, these being reciprocably received within the guide portions of the guiding members 120 and 121, respectively.

Supported between the frame side members 106 and 107 is a shaft 122, which serves to pivotally support a walking beam 123. The latter, on opposite sides of the shaft 122, is pivotally connected to the connecting rods 124 and 125, respectively, the latter being pivotally connected to the flanges 118 and 119 of the cleaning members 113

and 114 in a manner similar to that already described.

Slidably engaging the guide portions 126 of the walking beam 123 is a connecting rod 127, the opposite end of which is bored to engage the pin 128 having the squared head 129 slidably mounted in the slot 130 of the disc 131. The outer end of the pin 128 is threaded and carries the nut 132, whereby the pin 128 may be locked in position at any point along the slot 130, thus adjusting the eccentricity thereof and the length of the stroke of the connecting rod 127. The disc 131 is mounted upon the shaft 133 emerging from one side of the reduction gear box 134, the opposite side of which is driven from the shaft 135. The latter is drivingly connected to the shaft of the motor 136, which when started causes the shaft 133 and the disc 131 to rotate.

In the operation of the modified form of machine shown in Figures 6 and 7 the motor is started and the machine moved over the carpet 16, while liquid is supplied thereto from the tank 108 through the pipes 109 and 110. The rotation of the disc 131 causes the connecting rod 127 to reciprocate and move angularly up and down, sliding in and out of the guideways 126 in the walking beam 123. This action causes the walking beam 123 to rock, moving the cleaning members 113 and 114 up and down in alternate succession. The resilient portions 115 and 116 of the cleaning members 113 and 114 engage the surface of the carpet in a manner similar to that previously described, forcing the liquid into the interstices thereof and cleaning the carpet in a thorough manner.

It will be understood that the bottom surfaces of the resilient cleaning members may be provided with projections, or vacuum cups, instead of the ribs or corrugations previously described (see Figures 11, 12, 13 and 14).

The modified form of machine shown in Figures 8 and 9 contains a sub-structure and roller structure substantially the same as that described in connection with Figures 1 and 2. In the super-structure of this modification, however, the cleaning members each comprises a resilient coating 141, integrally attached to the C-shaped bracket 142, the upwardly extending arms of which are provided with inwardly directed flanges 144 bent around the cleaning member support plate 140 (Figure 9). A series of springs 143 urges the bracket 142 downwardly so that its flanges 144 normally engage the support plate 140 when the coating 141 is out of contact with the work. The coatings 141 are provided with corrugations, or other roughened portions 145, similar to those previously described, and have the same purpose. The cleaning members are rhomboidal or diamond shape in outline, this shape being provided so that no portion of the carpet will be free from the action of the pressing members. Thus the leading points of the spaces 146 between the adjacent cleaning members are farther to one side than the trailing points thereof, this overlapping feature preventing a seam of unclean carpet, which might occur if the spaces 146 were made parallel to the longitudinal direction of motion of the carpet.

The cleaning members support plates 140 are provided with vertically disposed flanges 147, which are attached to the yokes 148 by the pivot pin 149 passing therethrough. The upper ends of the yokes 148 are pivotally connected, as at 150, to the connecting links 151, the opposite ends of which are pivotally connected, as at 152, to the

walking beams 153. The latter are keyed or otherwise fixedly mounted upon the cross shaft 154 so that when the cross shaft 154 is turned backwardly and forwardly through a limited angle, the walking beams 153 will rock back and forth.

It will be observed that each end of each walking beam 153 carries a connecting link 161, member 140 and resiliently mounted coating 141 therefor. Consequently, when the walking beam 153 is rocked to and fro the resiliently mounted coatings rise and fall and alternately engage different portions of the carpet on opposite sides of the roller 19, located between them. By this action each portion of the carpet is given an intensive cleaning treatment, and no amount of warping of the mechanism can destroy or detract from this treatment because of the resilient mounting and the plurality of overlapping cleaning members used.

The cross shaft 154, carrying the walking beams 153, is rotatably mounted in bearings in the frame side members 3, 4 and 53, and the outer end on one side thereof is provided with a crank arm 155, keyed or otherwise securely mounted thereon. The outer end of the crank arm 155 has a threaded hole 156 adapted to receive a threaded rod 157, on the lower end of which is mounted a ball 158. The rod 157 is adjusted by screwing it in or out of the threaded hole 156 and is locked in position by means of the locknut 159.

The ball 158 is received within a correspondingly shaped socket 160 in the upper end of a connecting rod 161. The lower end of the connecting rod 161 is pivotally joined, as at 162, to a yoke 163, encircling a cam 164 securely mounted upon the drive shaft 165. The cam yoke 163 is provided with side plates 166 and 167, located respectively on each side of the cam 164, and tending to engage the faces thereof to prevent relatively longitudinal motion between the cam 164 and its yoke 163. The drive shaft 165 is mounted in bearings 168, located upon brackets 169, attached to the frame of the machine (Figure 8). The drive shaft 165 is provided with a pulley 170, carrying a belt 171, whose opposite end encircles a pulley 172 mounted upon the drive shaft of the main driving motor 173.

In the operation of the modified machine shown in Figures 8 to 10, inclusive, the rotation of the drive shaft 165 by the motor 173 and the belt 171 causes the cam 164 to rotate eccentrically, causing the yoke 163 to rise and fall, giving a corresponding rising and falling motion to the connecting rod 161 and the ball rod 157. This, in turn, causes the crank arm 155 to execute

oscillations through a limited angle, resulting in the oscillation of the cross shaft 154 and the rocking of the walking beams 153. This operation finally causes the cleaning members 140 to rise and fall in alternate succession, the spring 143 being compressed after the coating 141 engages the carpet and until the cleaning member 140 reaches the lowest position in its vertical descent.

The remainder of the machine is operated and the carpet caused to move in a manner similar to that already described. It will be observed that as the carpet moves under the coatings 141 of the cleaning members different portions of the spaces 146 therebetween will lie at different points over the width of the carpet, and therefore any uncleared portion in the spaces 146 will be previously or subsequently subjected to the action of some portion of one of the resilient coatings 141, due to the diagonal direction of the spaces 146.

It will be understood that I desire to comprehend within my invention such modifications as come within the scope of the claims and the invention.

Having thus fully described my invention, what I claim as new and desire to secure by Letters Patent, is:

1. In a carpet-cleaning machine, a movable support for the carpet, means for supplying a cleaning solution to the carpet, a pair of vertically reciprocable cleaning members positioned to engage the carpet, and means for moving said cleaning members alternately into engagement with the carpet, each of said cleaning members including a rigid horizontally disposed backing member carrying on the lower surface thereof a sponge rubber pad having spaced downwardly extending projections engageable with the carpet for pressing the cleaning solution into the carpet, the lower ends of said downwardly extending projections terminating substantially in a horizontal plane.

2. In a carpet-cleaning machine, a movable support for the carpet, means for supplying a cleaning solution to the carpet, a pair of vertically reciprocable cleaning members positioned to engage the carpet, and means for moving said cleaning members alternately into engagement with the carpet, said cleaning members including a rigid horizontally extending backing member having secured to its lower surface a yielding pad having resilient walled vacuum cups thereon for forcing the cleaning solution into and out of the carpet during the yielding of said vacuum cups.

JOHN K. TINGLE.
